CLAIM

The ornamental design for a battery-powered portable blender, as shown and described.

DESCRIPTION

FIG. 1 is a top-left perspective view of a battery-powered portable blender showing the new design;

FIG. 2 is a front view thereof;

FIG. 3 is a rear view thereof;

FIG. 4 is a right view thereof;

FIG. 5 is a left view thereof;

FIG. 6 is a top view thereof; and,

FIG. 7 is a top-left perspective view of the battery-powered portable blender showing another implementation of the new design.

The portions shown in broken lines form no part of the claimed design.
